CLAIM

We claim the ornamental design for a portable terminal, as shown and described.

DESCRIPTION

FIG. 1 is a perspective front view of a portable terminal according to the present invention.

FIG. 2 is right side elevation view of the portable terminal of FIG. 1.

FIG. 3 is a left side elevation view of the portable terminal of FIG. 1.

FIG. 4 is a rear elevation view of the portable terminal of FIG. 1.

FIG. 5 is a front elevation view of the portable terminal of FIG. 1.

FIG. 6 is a top view of the portable terminal of FIG. 1; and, FIG. 7 is a bottom view of the portable terminal of FIG. 1. The broken lines depict unclaimed features of the portable terminal, shown for purposes of illustration, and form no part of the claimed design.

1 Claim, 7 Drawing Sheets
